BOUDOIR LAMP

Ersyl F. Chambliss, Chicago, Ill.

Application January 3, 1938, Serial No. 183,038

6 Claims. (Cl. 240—4.2)

This invention relates to lamps and, more particularly, to boudoir and like lamps, although it is to be understood that the invention is not limited in all respects to use in lamps for the particular purpose mentioned but may be employed in all similar or equivalent lamps as suitable or desired.

One of the main objects of my invention is to provide an improved lamp having a shade provided with a mirror so arranged in concealed position therein as not to interfere with or detract from the useful purposes of the lamp, and which mirror is adapted for make-up or other use.

15 Further objects and advantages of my invention will appear from the following detailed description taken in connection with the accompanying drawing, in which:

Figure 1 is a perspective view of a lamp embodying my present invention;

Figure 2 is a vertical section through the shade of the lamp shown in Figure 1, taken on the line 2—2 of Figure 1;

Figure 3 is a vertical section similar to Figure 2, showing another embodiment of the invention;

Figures 4, 5 and 6 are sectional views of several forms of mirrors for use within the lamp shade in accordance with my present invention; and

Figure 7 is a side elevational view of another embodiment of my invention with the lamp shade and mirror in section.

Referring first to the embodiment of the invention illustrated in Figures 1 and 2, the lamp therein shown comprises a base 5 of any suitable or preferred construction on which is mounted an electric socket 6 for an electric lamp 7. Conductor means 8, connected to the socket 6, leads 40 out from the base 5 for connection with any suitable outlet, and a suitable switch may be provided as indicated at 9.

The shade 10, which may be of any suitable or preferred form, is supported upon the upper 45 end of the base 5 in horizontal position surrounding the electric lamp 7, the particular shade shown being of downwardly flaring, generally circular form, open at the top at 11 and at the bottom at 12. The shade may comprise 50 a frame covered with silk or any fabric or other suitable material for decorative as well as lighting purposes.

For mounting the shade upon the base 5, the interior of the shade may be provided with a 55 plurality of arms 14 extending inwardly and

downwardly from the annular frame piece 15 to a fitting 16 which fits removably upon the upper end of the base 5 at 17.

The shade 10 has fixed therein a mirror 20 disposed in concealed position within the shade 5 horizontally above the electric lamp 7 with the mirror surface directed upwardly, and with an annular space 21 between the periphery of the mirror and the shade for transmission of light upwardly around the mirror as well as outwardly through the shade and downwardly through the open bottom 12 thereof. The arms 14 have offset portions 22 upon which the bottom of the mirror frame 23 is seated and to which it is fixed rigidly or removably, as suitable or desired. 15 The bottom of the mirror 20 has the usual silvered or reflecting coating.

The lamp thus has the usual lamp functions, and, at the same time, the mirror 20 is disposed horizontally in concealed position in the shade 20 and normally exposed upwardly so that by looking down into the top of the shade 10 the mirror 20 is presented for use in making up the coiffure and applying cosmetics. The light transmitted up around the periphery of the mirror 20 assures 25 adequate light so that the mirror will properly reflect upwardly the face of a person looking down into the mirror through the open top 11 of the shade.

The upper end of the stem part of the base 30 5 is preferably pivoted at 60 to the lower end of the stem part of the base so that the shade may be tilted to direct the open top of the shade toward the face of the person in a generally horizontal direction or at any other desired angle. 35 This makes it unnecessary for the person to bend over the top of the shade to look into the mirror 20.

In the embodiment of the invention illustrated in Figure 3, the mirror 20a, instead of being spaced peripherally from the interior of the shade 10a, extends out to the shade and is provided with a central opening 25 through which the light from the electric lamp 7a is transmitted upwardly to provide illumination so that 45 the mirror will properly reflect upwardly the face of a person looking down into the mirror, as in the preceding embodiment of the invention. In this case, the pivotal connection shown at 60 in Figures 1 and 2 is omitted. The mirror frame 23a may be secured directly to the interior of the shade 5a, or to the frame thereof, and seats loosely upon the out-turned upper ends of the arms 14a extending from the fitting 16a mounted upon the upper end of the base 5a. 55

In Figure 4, the mirror 20b has a blank or frosted center 30 through which the light is transmitted through the reflecting coating 31 on the bottom of the mirror instead of an opening 5 entirely through the mirror as in Figure 3.

In Figure 5, the mirror 20c has a central opening or central blank or frosted area 32 over which is placed an opaque shield 33 which directs the light transmitted upwardly through 10 the blank or frosted area out through the mirror above the bottom silvering or reflecting coating 34, or out over the top surface of the mirror.

In Figure 6, the openings 36, through which 15 the light is transmitted through the bottom silvering or reflecting coating 37 of the mirror 20d, are disposed out near the outer periphery of the mirror, it being understood that any suitable number and arrangement of such openings 36 20 may be employed.

It is to be further understood that the mirror 20 shown in Figures 1 and 2 may have a central opening as shown in Figure 3, or it may be formed as shown in Figures 4, 5, or 6, or otherwise, for transmission of light therethrough, in 25 addition to the light which is transmitted upwardly around the periphery of the mirror.

In Figure 7, the shade 40, electric lamp 41, and mirror 42 are carried by an arm 43 pivoted 30 at 44 upon the goose-neck upper end 45 of the base 46, so that the shade, electric lamp, and mirror may be swung from normal horizontal position shown in full lines, to the position shown in dotted lines. In this embodiment of the invention, the mirror 42 is normally disposed horizontally beneath the electric lamp 41, with its silvered or reflecting surface 48 at the top, and with the mirror surface directed downwardly. A conductor or connector cord is shown at 49, and 40 a suitable switch is shown at 50.

A person desiring to use the mirror 42 swings the shade 40 to its dotted line position, and then looks into the mirror 42 generally horizontally from the front and through the open bottom 52 45 of the shade, instead of down through the top of the shade and generally vertically as in the embodiment shown in Figures 1, 2 and 3. With the shade 40 in its dotted line position, the electric lamp 41 is positioned behind the mirror 42 50 and the light rays are transmitted forwardly through the annular space 54 between the shade and the periphery of the mirror. The mirror 42 is shown also with a central opening 55, which may be omitted, or the mirror may be formed 55 as shown in Figures 4, 5 and 6, or otherwise as suitable or desired.

I do not intend to be limited to the precise details shown or described.

I claim:

60 1. A lamp comprising an upright base, an electric lamp carried at the upper end of said base, a shade open at the top and at the bottom, means secured in concealed position to the interior of said shade for supporting the shade upon the upper end of the base in position surrounding said lamp, and a mirror supported by 65 said concealed shade supporting means in concealed position within said shade, said mirror being normally positioned horizontally above the lamp with its reflecting surface directed upwardly and 70 visible through the open top of the shade and with the open bottom of the shade directed downwardly for passage of the light from said lamp therethrough.

75 2. A lamp comprising an upright base, an elec-

tric lamp carried at the upper end of said base, a shade open at the top and at the bottom, means secured in concealed position to the interior of said shade for supporting the shade upon the upper end of the base in position surrounding said lamp, and a mirror supported by said concealed shade supporting means in concealed position within said shade, said mirror being normally positioned horizontally above the lamp with its reflecting surface directed upwardly and 10 visible through the open top of the shade and with the open bottom of the shade directed downwardly for passage of the light from said lamp therethrough, said mirror having a central portion through which light is adapted to be 15 transmitted upwardly from said lamp when said shade is in horizontal position with the open top of the shade directed upwardly and the open bottom of the shade directed downwardly.

3. A lamp comprising an upright base, an electric lamp carried at the upper end of said base, a shade open at the top and at the bottom, means secured in concealed position to the interior of said shade for supporting the shade upon the upper end of the base in position surrounding said lamp, and a mirror supported by said concealed shade supporting means in concealed position within said shade, said mirror being normally positioned horizontally above the lamp with its reflecting surface directed upwardly and 20 visible through the open top of the shade and with the open bottom of the shade directed downwardly for passage of the light from said lamp therethrough, said mirror being supported concentrically within the shade with a space between the periphery of the mirror and the interior of the shade through which light is adapted to be projected upwardly from said lamp when said shade is in horizontal position with the open top of the shade directed upwardly and the open 25 bottom of the shade directed downwardly.

4. An ornamental boudoir lamp comprising an upright base, an electric lamp carried at the upper end of said base, an ornamental shade open at the top and at the bottom, a plurality of arms secured in concealed position to the interior of the shade and extending inwardly therefrom and secured to said base for supporting said shade on said base in position surrounding said lamp, and a mirror supported by said concealed shade supporting arms in concealed position within said shade, said mirror being normally positioned horizontally above the lamp with its reflecting surface directed upwardly and 30 visible through the open top of the shade and with the open bottom of the shade directed downwardly for passage of the light from said lamp therethrough.

5. A lamp comprising an upright base, an electric lamp carrying part pivoted to the upper end 60 of said base, an electric lamp carried by said lamp carrying part, a shade open at the top and at the bottom, means secured in concealed position to the interior of said shade and to said pivoted lamp carrying part for supporting the shade upon the upper end of the base in position surrounding said lamp and for pivotal movement with said lamp, and a mirror supported by said concealed shade supporting means in concealed position within said shade, said mirror being positioned horizontally above the lamp in the horizontal position of the shade, with its reflecting surface directed upwardly and visible through the open top of the shade and with the open bottom of the shade directed downwardly 70

for passage of the light from said lamp there-through.

5. A lamp comprising an upright base, an electric lamp, a shade open at the top end and at the bottom end, means secured in concealed position to the interior of said shade for pivotally supporting the shade upon the upper end of the base in position surrounding said lamp, and a mirror supported by said concealed shade sup-

porting means in concealed position within said shade, said mirror being normally positioned substantially horizontally when the shade is in position with its open ends directed vertically and being visible through one of the open ends of the shade when the shade is swung into position with said open end of the shade directed generally horizontally.
